(57) **CLAIM**

The ornamental design for a handle for use with a medical retrieval instrument, as shown and described.

DESCRIPTION

FIG. 1 is a perspective view of a handle for use with a medical retrieval instrument showing our new design; FIG. 2 is a top plan view thereof;

FIG. 3 is a bottom plan view thereof;

FIG. 4 is a left side elevational thereof;

FIG. 5 is a right side elevational view thereof;

FIG. 6 is a front elevational view thereof;

FIG. 7 is a rear elevational view thereof; and,

FIG. 8 is another perspective view thereof.

The broken lines shown on the figures depict environmental subject matter only and are hereby disclaimed as forming no part of Applicants' claimed invention.
